Arrow Metal Products Corp. Inc., Haskell, N.J., a cor-
poration of New Jersey

Application July 26, 1957, Serial No. 47,100

Term of patent 14 years

(Cl. D13—1)

Figure 1 is a view in perspective of a double free-standing outdoor shelter, showing my new design; and,

Figure 2 is a top plan view of the double free-standing outdoor shelter shown in Figure 1;

Figure 3 is a cross-sectional view taken on line 3—3 in Figure 1 looking in the direction of the arrows; and

Figure 4 is a transverse sectional view taken on line 4—4 of Figure 1.

I claim:

The ornamental design for a double free-standing outdoor shelter, substantially as shown.
